UNITED STATES PATENT OFFICE.

ALEC STEIN AND GEORGE STEIN, OF NEW YORK, N. Y.

FINGER-PROTECTOR.

1,388,618.

Specification of Letters Patent. Patented Aug. 23, 1921.

Application filed June 17, 1920, Serial No. 389,557. Renewed July 14, 1921. Serial No. 484,818.

To all whom it may concern:

Be it known that we, ALEC STEIN and GEORGE STEIN, citizens of the United States, and residents of New York city, in the 5 county of New York and State of New York, have invented certain new and useful Improvements in Finger-Protectors, of which the following is a specification.

This invention relates to finger protectors or finger safety guards. The object of 10 the invention is to provide shields or protecting guards adapted to be securely positioned on the forefinger and thumb of the hand so as to protect the fingers against injury from cutting implements, grind stones, 15 polishing stones and like apparatus or devices in the operation of which the fingers of the operator are exposed to injury.

One object of the invention is to provide 20 a finger guard adapted to protect and cover the two first joints of a finger while permitting full freedom in the use of the finger to grasp even tiny objects.

Another object is to provide a finger 25 guard comprising a plurality of sections so secured or attached to each other that the natural use of the fingers, in bending for instance, is not impaired or hindered.

Still another object is to provide finger 30 guards of simple and inexpensive construction together with simple and efficient means for attaching the guards to the hand.

With the above and other objects in view, 35 our invention is embodied in finger guards constructed and arranged as hereinafter set forth while reference is had to the accompanying drawing in which—

Figure 1. is a front view or end view of 40 a finger guard embodying the invention.

Fig. 2. is a side view of the guard.

Fig. 3. is a top plan view of the guard.

Fig. 4. is a bottom view, and

Fig. 5. is a view showing the guard applied to the forefinger and thumb of a 45 hand.

Our improved guard consists of two sections, an outer or front section 6 and an inner or rear section 7. The outer section is shaped to form a top shield portion 8 and side portions 9, 9 which merge into bottoms or inside retaining lugs 10, 10. The front section is further provided with rearwardly extending hinge lugs 11, 11 provided with a pivot 12, one on each side. The pivots 12 50 may be formed by being struck up or punched up from the body of the lugs 11.

The forward portion 25 of the front section forms a finger tip protecting wall.

The rear section 7 is formed with a top shield portion 15 extending forwardly as at 60 16 to closely fit the rear edge 17 of the forward portion 6. The rear section further forms downwardly extending curved side portions 18, 18 which merge into inside or bottom lugs or wings 19, 19. From the side 65 portions 18 extend forwardly the hinge lugs 20, 20 which have punched up sockets 21, 21 adapted to receive the pivots 12 aforesaid. 22 is an aperture in the rear section 7.

The finger guards will be formed of suitable material, either cast, stamped or drawn or otherwise formed. The material may be metal, rubber, celluloid or a composition. It may be non-transparent or transparent or translucent. The guard will further be 70 shaped to follow as closely as may be the usual shape of the fingers and may be provided in sizes to fit and in shapes to be used on one, two or more fingers of the hand. As ordinarily only the forefinger and thumb 75 are used to grasp objects, only corresponding finger guards are shown in Fig. 5.

It is preferable to make the guards of slightly springy or yielding material as 80 thereby provision is made for pressing together the lugs 10, 10 and 19, 19 to suit the thickness of the fingers.

As shown in Fig. 5 the guards are used by placing them over the tip or ends of the fingers with the shields uppermost. It will 90 be seen then, as shown, that the two outer joints of the fingers are protected without impairing their use. The fingers may be bent in gripping or handling objects and the finger pads as indicated at 30 remain exposed.

The guards bend on the hinges or pivots 95 12 as shown and in securing them to the hands an elastic 35 may be used which is simply crossed before passing it around the 100 wrist as at 36. An elastic is preferable because it yields to the natural movement of the fingers while working and retains the guard on the finger securely, yet without undue strain or pull.

The two sections of the guard are made 105 separately and joined securely by snapping the outside hinge lugs 20, 20 over the inside hinge lugs 11, 11 whereby the pivots 12 snap into place and whereby rivets and screws 110 are eliminated.

Fig. 5 illustrates the fingers in the natural

position of gripping a tiny object and it will be seen that but very little of the knuckles on the hand are exposed. On the other hand, when the finger is straight it is completely protected as is clear from Fig. 2.

The elastic may remain as a fixed part of the guards by tying it securely in the holes 22 as it will yield sufficiently in removing or attaching the guards to the fingers.

10 It will further be understood that we do not intend to limit our invention by what has been disclosed in the foregoing, but that changes and modifications may be made without departing from the principle of the 15 invention and within the scope of the appended claims.

We claim:—

1. A finger guard comprising an outer finger tip section and a rear section, means 20 for pivoting the one section upon the other, both of said sections being substantially semi-circular in cross section and each of said sections having bottom retaining lugs, and means for attaching the said finger 25 guard to the hand of the user thereof.

2. Finger guards for the two first joints of the forefinger and the thumb, each of said guards comprising an outer finger tip section and a rear or inner section pivoted one 30 upon the other and an elastic having its free

ends secured to the said inner sections for securing the said finger guards to the hand of the user.

3. A finger guard consisting of a finger tip section and a rear section, each of said 35 sections being formed to provide a top and side protecting portions, each of said sections being provided with inside or bottom retaining lugs, which latter serve as means for adjusting said sections circumferentially 40 and means for pivoting one of the said sections on the other section.

4. A finger guard comprising a finger tip section having an outer depending finger tip protecting wall and a rear curved edge portion, a rear guard section having a forwardly extending top portion adapted to conform and fit closely to the said rear edge 45 of the finger tip section, pivots formed in the latter, pivot receiving recesses formed 50 in said rear section for pivoting the finger tip section within the said rear section and means for attaching the said guard to the hand of the user thereof.

Signed at New York, in the county of 55 New York and State of New York, this 15th day of June, A. D. 1920.

ALEC STEIN.
GEORGE STEIN.
